UNITED STATES PATENT OFFICE.

JOHN A. JUST, OF SYRACUSE, NEW YORK.

APPARATUS FOR MAKING CHLORINE.

SPECIFICATION forming part of Letters Patent No. 391,158, dated October 16, 1888.

Application filed April 14, 1888. Serial No. 270,708. (No model.)

To all whom it may concern:

Be it known that I, JOHN A. JUST, of Syracuse, in the county of Onondaga, in the State of New York, have invented new and useful 5 Improvements in Apparatus for Making Chlorine, of which the following, taken in connection with the accompanying drawings, is a full, clear, and exact description.

This invention relates to an improvement in 10 apparatus for making chlorine; and it consists in certain novel details of the construction and arrangement of the same, substantially as will be hereinafter more fully set forth, and more specifically pointed out in the claims.

15 In order to enable others skilled in the art to which my invention pertains to make and use the same, I will now proceed to describe its construction and operation, referring to the accompanying drawings, in which—

20 Figure 1 is a diagram view of a plant arranged as I shall describe. Fig. 2 is a transverse section of a part of the plant used for recovering the manganese dioxide and nitric acid, part of the devices appearing in elevation. Fig. 25 3 is an enlarged detail section of one of the stills or generators, showing its connections to the different pipe systems, and also the manner of operating the siphon. Fig. 4 is a section taken longitudinally through the washer. Fig. 5 is 30 a detail plan view of the trap into which the lower end of the siphon is received, and through which the residue liquor is entered to the drain and conducted to the cistern or well; and Fig. 6 is a detail cross-section of the pan 35 placed over the furnace to separate the constituents of the residue liquor and recover the manganese dioxide.

In the manufacture of chlorine on a large scale, commercially, a number of stills or generators are required, and as I desire in this apparatus to so arrange the parts that the process of manufacture shall be practically continuous and there will be a continuous charging of the stills, recovery of the ingredients, 40 and immediate reuse of the same, I have arranged my stills or generators in a series of rows or batteries connected with the charging and recovery devices by a series of pipe systems arranged, as shown, to be out of the way 45 of the operators and attendants in their work, but in perfect position to best carry on the

work continuously, as will be now described fully and in detail.

I use any desired and suitable number of stills in the formation of a battery, the series 55 forming each battery being placed in a trough, *a*, preferably of wood, lined with sheet-lead of requisite strength, as clearly indicated at *a'*, and in the bottom of the trough I place a coil of steam-pipes, *a''*, for heating the stills, as will be hereinafter more fully explained.

Each still or generator consists of an earthenware vessel, *b*, of suitable size and form, which vessel is provided with a removable cap or cover, *b'*, the rim of which fits into a groove, 65 *b''*, in the top of the still, and this groove is filled with water or other liquid to form a seal, into which the rim of the cover is received, and the admission of air or escape of gas around the edges of the cover is thus effectually prevented, while the cover is readily removed or replaced as it becomes necessary in the working of the apparatus.

Upon one side of the still, in its side wall, is formed a passage, *c*, the lower end of which 75 opens inwardly to the interior of the still at or near its bottom, while the upper end of said passage opens outwardly through the side of the still at a suitable height, and to this opening is secured a section of rubber tubing, *c'*, 80 connected to a glass tube, *c''*, which latter is extended downward and opens into a trap, *c'''*, seated upon the drain system, which carries off the residue liquor after the charge in a still is fully worked. All this will be fully seen in 85 Figs. 1 and 3.

The passage in the side of the still, together with the rubber and glass connections, forms a siphon for draining the still of its residue liquor, and this siphon is started and operated by a simple contrivance, (shown in Fig. 3,) as follows: Above and at one side of the still I secure two shelves, *d d'*, one above the other. Upon the upper shelf is a pair of air-tight jars, *d'*, containing liquid—such as water—95 which partially fills them, and connected by a flexible tube, *d''*, as shown. One of the jars is also connected by a rubber tube, *d'''*, with the siphon and provided with any suitable compress, *d''''*. When the siphon is to be started, 100 the second jar is lowered to the lower of the two shelves and the compress *d''''* is loosened.

This at once causes the liquid in the upper jar, d' , to flow into the lower one and draws the air out of the siphon till the residue liquor rises in the passage c and flows over through 5 the rubber and glass tubes. As soon as this flow is started the compress is tightened, the second jar returned to its place on the upper shelf, and the siphon continues to draw off the residue liquor from the still to the drain till 10 all has been exhausted and the still is empty. This forms a very efficient mode of emptying the stills, which needs little attention, and is automatic in its action after having been started.

15 It is evident that a glass tube may be used upon the inside of the still to take the place of the passage c ; but I prefer the form described with this passage formed in the still body, as shown. It will be understood that each still 20 of the battery is provided with its own siphon connected to the drain exactly as has just been described.

Within the still is placed a perforated vessel, e , to receive and hold a portion of the 25 charge, and the top or upper part of the still is upon one side of its central opening provided with a nozzle, e' , for the escape of the chlorine gas, which nozzle is connected to a gas-conducting system, presently described.

30 Upon the opposite side of the central opening the still-top is provided with another opening, e^2 , which is formed with a grooved flange, e^3 , in which rests a cover, e^4 , having its rim on its lower edge notched out, as shown, and this 35 forms an inlet for the reception of the acid charge which flows under the notched edge of the cover, and so enters the still, sufficient always remaining in the groove to form a seal to the cover in the same manner as described for 40 the main cover of the still, and so prevent the gas from escaping as it forms therein, except by the opening provided for it.

In a plant of any size the batteries are arranged in parallel rows, as in Fig. 1, with sufficient space left between them for the free 45 and convenient passage of the workmen and attendants; and at a convenient point I construct, in the ordinary way, of stone and cement, a tank or cistern, f , for the reception of the residue liquor left in the stills after the 50 working of a charge, which liquor contains certain elements which it is necessary to recover, and must therefore be saved till subjected to the recovery process. From this cistern a main drain, f' , is laid (preferably under- 55 ground, so as to be out of the way) past the ends of the batteries of the plant, and of course with an inclination toward the cistern, so the liquor may run freely through it. Connected 60 to this main drain are a series of branch mains, f^2 , which are extended laterally alongside of the series of batteries, and in each of these branches, at proper intervals, is inserted a trap, c' , as best shown in Figs. 3 and 6. 65 These traps simply consist of small cups suspended by lugs in openings of the drain, and

their object is to retain sufficient liquid to seal the lower ends of the siphons which rest in them. Each trap is by a siphon such as I have already described connected to one of the stills of the battery, and thus when these siphons are started the residue liquor contained in the stills is automatically drawn off and flows readily through the branch and main drains to the cistern. These mains and the 75 cistern are clearly shown by dotted lines in Fig. 1, and their location and operation will be clearly understood.

The acids used in the manufacture by my process are two in number—viz., hydrochloric acid and nitric acid. These are contained in a divided receptacle, g , conveniently located, and each provided with a draw-off cock which empties into the open ends of a T , g' , connected to an acid-main, g^2 , which is extended 85 down past the ends of the batteries, as in Fig. 1, inclining away from the acid-receptacle to give a free flow of the same, and this acid-main is also provided with a series of branches, g^3 , extending laterally past the stills of the batteries. These branch and main pipes are connected by two-way cocks, so that the whole flow of acid may be directed from the main into any particular branch at pleasure, and each branch is provided also with a series of discharge-cocks, g^4 , corresponding to the number of stills on the line, and these discharge-cocks convey the acids to the receiving-openings of the stills. In the charging of the stills it is always advisable to begin with the still nearest the main acid-pipe and charge them consecutively, as it is thereby possible to drain out all the acid in the pipes at the charging of the last still of the series or battery. This is a matter of advantage in practice that will be at once clearly 95 seen.

It will be noted that the arrangement of the acid supply system being above the stills is out of the way of the attendants and does not interfere with them in their duties, and that 100 the connections to the stills are such that any one or all of the stills are charged at pleasure, and thus each still is under independent control and can be worked separately from the rest of the battery.

Alongside of each line of stills or batteries, and above the same, out of the way, is also arranged a branch gas-pipe, h , to which the gas-outlet of each still is connected by a pipe, h' , of lead or material to resist the action of the chlorine. These pipes h' , as seen in Fig. 3, are preferably carried above the gas-pipe h and connected thereto by a bend, in order that the moisture which may be carried into the pipe by the gas shall not be drained back into the 120 stills, but shall run through the gas system to the washer, where it can do no harm. These gas branch pipes all connect with a main gas-conductor, h , which is connected to a washer, i , as in Figs. 1 and 4, in which the gas is forced 125 to spread out, and passes over the surface of water, as illustrated. From thence the gas- 130

conductor is led off to its connection with the chloride-of-lime chambers ⁵ at any convenient point.

Some of the ingredients used in the manufacture of the chlorine are to be recovered from the residue liquor for reuse, and to accomplish this I use the devices as follows: A furnace, *k*, of any suitable size and economical form and construction, is located conveniently, and over it is set a shallow pan, *k'*, closed in, as shown in Fig. 2. In this pan I place the residue liquor from the cistern and apply heat from the furnace at a slowly-rising temperature till the maximum heat is obtained for the purpose intended. The closed pan is connected by a pipe, *k*², with a condensing-tower, *k*³, provided with an air-inlet, *k*⁴, near its lower end. Within the tower are arranged a series of shelves, *m*, having openings arranged therein at alternate sides, and in the upper part of the tower is provided a jet or spray of water, as at *m'*, which flows down over the shelves through their zigzag openings to the bottom. A series of condensing-jars, *m*², are provided, connected together by pipes *m*³ and siphons *m*⁴, and the upper end of the condensing-tower *k*³ is connected by a pipe, *n*, with the first one of the series of condensing-jars, this pipe passing through an intermediate cooler, *n'*, as clearly seen in Fig. 2. The lower end of the tower is also connected by a glass tube, *n*², with the last jar of the series, as clearly illustrated. From the last jar of the condensing series a pipe, *o*, extends to a second tower, *o'*, also provided with a water jet or spray, and having from its lower end a glass tube, *o*², for conducting the slightly-acid water back to the last jar, as shown.

When the heat is applied in the furnace, the residue liquor is caused to throw off one of its ingredients in nitrous vapors and the other is finally left solidly in the pan in the form of pure manganese dioxide. The nitrous vapors pass off through the proper connections to the tower *k*³, where they are mixed with air, and rise over the shelves through the tower, and are cooled and greatly condensed by contact with the water flowing down. The condensed vapors, forming weak acid, are carried from the bottom of the tower to the last jar of the condensing series, and are caused to travel through the series toward the first jar. The uncondensed vapors and commingled air pass off at the top of the tower through the pipe *n* to the first of the series of jars and pass on through the series, subject to contact with and in the opposite direction to the acid-water.

Should any uncondensed vapors remain on reaching the end of the series of jars, they pass on to the second tower, and are there thoroughly condensed and returned to the end of the series, as shown. Thus I obtain a perfect recovery of both the ingredients contained in the residue liquor, and reuse them in again charging the batteries, effecting a considerable economy in practice and making the process of manufacture by the peculiar arrange-

ment of the plant practically continuous, and it is not necessary to check the work while cleaning and recharging the stills. ⁷⁰

The advantages of this arrangement of the plant will be obvious. It can not only be worked in whole or in part, according to the demand for the product, but it is very cheaply and quickly enlarged at any time by simply extending the pipe and drain systems and adding another battery, or by adding more stills to the batteries already in use and extending their size. The arrangement is also compact, and in such form as to permit the work to be ⁷⁵ done automatically and under perfect control.

I have named herein as the ingredients used in the apparatus nitric acid, hydrochloric acid, and manganese dioxide, because these form the ingredients used in a process for which I ⁸⁰ have applied for a separate patent of even date herewith, and this apparatus is the one I prefer to use in carrying out said process; but I do not desire to be understood as in any way confining myself thereto, as other processes ⁸⁵ and combinations of ingredients may be worked and recovered in this apparatus with equal facility.

Having thus fully described my invention, what I claim as new, and desire to secure by ⁹⁰ Letters Patent, is—

1. The combination, with a series of stills arranged in batteries, of an acid-supply tank provided with a system of distributing-pipes separately connected to each still, a system of ⁹⁵ drain-pipes also connected to each still and to a cistern, and a system of gas-pipes separately connected to each still and led through a washer to the desired point, all constructed and arranged to operate substantially as and for the ¹⁰⁰ purpose set forth.

2. The combination, with a drain system and a cistern to which it leads, said drain being provided with a series of traps at proper points, of a series of stills each connected to one of ¹⁰⁵ the traps by a siphon, substantially as and for the purpose set forth.

3. The combination, with a still provided with a siphon for emptying it, of a drain system, *f'* *f*², provided with the cup-shaped traps ¹¹⁰ *f*³, for holding liquid, in which the end of the siphon is sealed, substantially as and for the purpose set forth.

4. The combination, with a still provided with a siphon for draining off the liquid residue after operation, of a pair of shelves, one above the other, a pair of liquid-vessels connected by a siphon-pipe and one of them adapted for removal from the upper shelf to the lower and back, and a pipe connecting the ¹¹⁵ other vessel with the still-siphon and provided with a compress cock, substantially as and for the purpose set forth.

5. The combination, with the condensing-tower and the series of connected condensing-jars, of a pipe for the vapors connecting the upper part of the tower with the first jar of the series, and a second pipe for the acid-water connecting the bottom of the tower with

the last of the series of jars, substantially as and for the purpose set forth.

6. The combination, with the series of condensing-jars m^2 , of a vapor-pipe connecting the 5 end of the series with the tower o' , and a return-tube, o^2 , connecting the base of this tower with the last jar of the series, substantially as and for the purpose set forth.

In testimony whereof I have hereunto signed

my name, in the presence of two attesting witnesses, at Syracuse, in the county of Onondaga, in the State of New York, this 10th day of April, 1888.

JOHN A. JUST.
